Ludwig Schön,
By Kaufmann Attorneys.

UNITED STATES PATENT OFFICE.

LUDWIG SCHÖN, OF ESSEN, GERMANY, ASSIGNOR TO FRIED. KRUPP AKTIENGESELLSCHAFT, OF ESSEN-ON-THE-RUHR, GERMANY.

SWITCH DRUM FOR STARTING AND CONTROLLING ELECTROMOTORS.

Application filed September 26, 1922. Serial No. 590,710.

To all whom it may concern:

Be it known that I, LUDWIG SCHÖN, residing at Essen, Germany, a citizen of the German Republic, have invented a certain new and useful Improvement in Switch Drums for Starting and Controlling Electromotors, of which the following is a specification.

This invention relates to improvements in switch drums for starting and controlling electromotors and has for its object to provide the switch drum with a device by means of which the drum can be locked in such a manner that an abnormally rapid return of the drum to a lower switch step is rendered impossible and that any inadmissibly high stress on the contacts designed to close or break the motor circuit is securely avoided.

The subject matter of the invention is of particular importance in connection with switch drums of the kind in which the motor circuit is not interrupted at the contact members of the switch drum itself but at an auxiliary electromagnetic cut-out situated outside the switch drum. This means that the device according to the invention is likewise adapted for use in cases in which it is held desirable to lock the drum also in the driving positions or solely in the same, while without the use of such an auxiliary cut-out the switch drum can only be locked in its braking positions.

The accompanying drawing diagrammatically illustrates, as an embodiment of the subject matter of the invention in connection with the wiring diagram of a D. C. tramcar motor, a controller which cooperates with an auxiliary electromagnetic cut-out serving to interrupt the motor circuit and which is automatically locked as long as the motor current exceeds a predetermined maximum value.

Referring now to the drawing, A designates the overhead line which is connected to the positive pole of a source of direct current and to which is connected by means of a trolley B a line C leading to the ground (negative pole). Placed in the line C so as to be connected in series with one another and with the switch drum K when the latter is in its driving positions, are: the releasing coil d^1 and the two break forming contact points d^2 and d^3 of a circuit-breaker D provided for protection of the plant against

overload, a multi-step starting resistance E, the winding f^1 of a magnet F that will still be further described, the two break forming contact points g^1 and g^2 of the auxiliary electromagnetic cut-out G as well as the armature H and the exciting winding H^1 of the D. C. motor to be controlled. The overload circuit-breaker D contains, in addition, another magnet coil d^4 which acts on the same magnet core as the main current releasing coil d^1 and which is wound in the same direction as the last mentioned coil. The magnet coil d^4 is connected in parallel to the break d^2 d^3 and is of a strength such as to be able to hold the opened circuit-breaker D in its cut-out position contrary to the action of a spring d^5 ; coil d^4 constitutes therefore a holding coil. The auxiliary cut-out G possesses only one magnet coil g^3 which is connected, on the one hand, to the contact point g^2 of the cut-out G and, on the other hand, to the outset of the first step of the starting resistance E. Interposed between the coil g^3 and the contact point g^2 is a resistance J by which any short-circuit is rendered impossible when the auxiliary cut-out G is closed. The magnet coil g^3 is proportioned so that it will be able to overcome the force of a spring g^4 counteracting the coil g^3 and open the cut-out G only in case it is put into direct connection with the full voltage of the source of direct current. This is rendered possible by the intermediary of an auxiliary switch device which forms part of the controller and will therefore be described in connection with the same.

The controller cooperating with the starting resistance E, consists of a switch drum K provided with contact bars and of a regulating lever K^1 which constitutes the driving means for the drum and which is rotatable round the axis of the switch drum for a slight angle with relation to the switch drum. In the drawing, the contact bars designed to start and control the motor H H^1 are omitted from the lower portion of the switch drum K; the terminals of the corresponding wipers are indicated by small circles k^2 at which terminates the connecting wires leading to the starting resistance E, the motor H H^1 and the poles of the source of direct current. The regulating lever K^1 is mounted for free rotation on the upper end face k^3 of the switch drum K by means

of a pin k^2 so as to be able to move with relation to the switch drum between two stops k^4 and k^5 which are likewise arranged on the end face k^3 at a small distance. The end face k^3 of the switch drum K further carries a one-armed lever k^6 which is provided with a projection k^7 adapted to engage a notch k^8 of the regulating lever under the influence of a spring k^9 . When the regulating lever 10 K^1 is not handled, it is forced by the engagement of the projection k^7 with the notch k^8 to take a position midway between the two stops k^4 and k^5 . The regulating lever K^1 possesses at its rear end an extension enlarged so as to form a sector k^{10} of a radius 15 somewhat larger than that of the switch drum K and having fastened to its edge, in the manner to be seen from the drawing, a metal rod k^{11} extending parallel with relation to the axis of the switch drum. The rod k^{11} constitutes a contact member which serves to conductively connect, in the limit positions of the regulating lever K^1 determined by the stops k^4 and k^5 , two of three 20 slightly resilient contact members k^{12} , k^{13} and k^{14} each of which is arranged on one of three contact bars k^{15} to k^{17} which are riveted in parallel radial planes to the switch drum K. The uppermost contact bar k^{15} 25 embraces approximately one half and the lowermost one k^{17} the other half of the circumference of the switch drum, while the intermediate bar k^{16} embraces nearly the entire circumference. The cooperating wipers k^{18} to k^{20} are arranged at a stationary portion 30 of the controller casing in a manner such as to bear against a part of the switch drum not covered by the contact bars when the switch drum K is in the position shown, in which it takes its zero position with relation to the casing (not shown). The intermediate contact member k^{13} of the three contact members k^{12} to k^{14} is constructed and arranged so as to be touched by the rod k^{11} 40 in each of the two limit positions of the regulating lever K^1 , while the two other contact members k^{12} and k^{14} are arranged so as to cause the rod k^{11} to engage the contact member k^{12} of the uppermost contact bar k^{15} when the regulating lever touches the stop k^4 , and to engage the contact member k^{14} of the lowermost contact bar k^{17} when the regulating lever touches the stop k^5 . On account of the described arrangement of the contact bars k^{15} to k^{17} , the intermediate contact bar k^{16} will be in engagement with the corresponding wiper k^{19} in all operative positions of the switch drum K except for the zero-position, while the uppermost contact bar k^{15} touches its wiper only in the driving positions and the lowermost one k^{17} only in the braking positions. The wipers k^{18} and k^{20} 55 are conductively connected with each other and by a line M to the point of connection 60

between the releasing coil g^3 of the auxiliary cut-out G and the series resistance J, while the wiper k^{19} is grounded through a line N. As will be readily seen from the drawing, the described switch connections will cause the magnet coil g^3 to be put under the voltage of the direct current source every time the regulating lever K^1 will be returned from any one of its operative positions towards the zero-position of the switch drum K, so that now, in the driving positions of the switch drum, the pair of contact members k^{12} , k^{13} , and in the braking positions the pair of contact members k^{13} , k^{14} , will be bridged by the metal rod k^{11} . 70 The switch drum K carries at its upper end a ring-sector-shaped extension k^{21} the margin of which is provided with a series of teeth k^{22} corresponding in number to the number of driving steps. The margin of the sector-shaped rearward extension k^{10} of the regulating lever k^1 is likewise provided with teeth k^{23} which, however, are arranged more closely to each other than the teeth k^{22} and are directed oppositely to the latter. 80 The toothed portions k^{22} and k^{23} thus form parts of two oppositely directed locking mechanisms which act each in one single direction and the cooperating parts of which are formed by two pawls P^2 and Q^2 85 influenced by the magnet F f^1 already mentioned. The pawl P^2 is pivotally and resiliently connected to one arm P^1 of a wrought iron bell crank lever P P^1 which is mounted on the casing of the controller 100 K K^1 and the other arm P of which has a thickened end p^4 facing one of the end faces of the magnet core F. The pawl Q^2 which is directed oppositely and mounted for swinging motion in a plane parallel to the pawl P^2 , is similarly pivoted to one arm Q^1 of another bell crank lever Q Q^1 , the other arm Q of which has its thickened end q^4 facing the other end face of the magnet core F. The two thickened ends p^4 and q^4 105 form armatures of the magnet F f^1 . A compression spring R engaging both the lever arms P and Q tends to hold the ends p^4 and q^4 apart from the end faces of the magnet F. The stroke of the two lever arms P 110 and Q pressed outwards by the spring R, is limited by two fixed stops P^3 and Q^3 in such a position that the pawls P^2 and Q^2 are out of engagement with the corresponding teeth k^{22} and k^{23} . The magnetic conditions of the double locking device F f^1 , P^2 , k^{22} , Q^2 , k^{23} 115 are proportioned so that, in case the strength of the motor current flowing through the coil f^1 when driving or braking electrically will exceed a predetermined maximum value, the magnet F f^1 will overcome the power of the spring R, attract the armatures p^4 and q^4 and move the pawls P^2 and Q^2 into the path of the teeth k^{22} and k^{23} , so that, according to the direction of ro- 120 125 130

6 tation of the regulating lever K^1 and the switch drum K , either one or the other of the two single acting locking devices P^2 k^{22} and Q^2 k^{23} will cause a locking of the controller K K^1 . A locking of the controller can therefore take place in the driving positions as well as in the braking positions of the switch drum. Both locking devices will, however, become inoperative as soon 10 as the motor current drops below the determined maximum value or the motor circuit is interrupted. In this case, the controller is free to be rotated in both directions of rotation.

15 With the end of describing the operation of the device set forth, it is assumed that all parts take the position illustrated in the drawing in which, more particularly, the regulating lever K^1 of the controller K K^1 takes the position in the middle between the stops k^4 and k^5 and the switch drum K is in 20 its zero-position, so that the motor circuit and the circuit of the auxiliary switch device containing the contact members k^{12} to k^{14} is interrupted at the switch drum and the magnet coils d^4 , g^3 and f^1 are currentless. The cut-outs D and G are therefore closed and the two locking devices P^2 k^{22} and Q^2 k^{23} are inoperative.

25 30 If the motor H H^1 should be started, the controller K K^1 has to be brought first into the position corresponding to the first driving step, this being effected by rotating the regulating lever K^1 in the direction of the arrow α . This movement will cause the projection k^7 to be disengaged from the notch k^8 and the regulating lever K^1 to become 35 engaged with the stop k^5 while the switch drum is still at rest. In this position, the metal rod k^{11} will establish a conductive connection between the contact members k^{13} and k^{14} and, consequently, between the contact bars k^{16} and k^{17} , but the circuit containing the contact members k^{12} to k^{14} will 40 still remain broken at the wipers k^{18} to k^{20} . In continuing the rotation of the regulating lever the switch drum K will likewise be moved in the direction of the arrow α and the motor circuit will close now in a well-known manner through the resistance steps 45 of the starting resistance E and the wipers indicated by the terminals k^{24} as well as through the main current contact bars (not shown) of the switch drum K . At the same 50 time, the wipers k^{18} and k^{19} will enter into touch with the corresponding contact bars k^{15} and k^{16} of the auxiliary switch device, while a contact between the wiper k^{20} and the contact bar k^{17} does not take place owing 55 to the peculiar construction of this contact bar. Therefore, no circuit will as yet be closed through the contact members k^{15} , k^{14} and the rod k^{11} , and the lines M , N will even remain currentless when the switch 60 drum is further rotated in the direction of

the arrow α , during which further rotation the speed of the motor armature H will gradually increase. A change will only take place when switching the controller back from any of its switch steps. As 65 soon as the regulating lever K^1 is moved in a direction opposite to the arrow α , the switch drum K will at first remain at rest and the metal rod k^{11} will come into touch with the contact members k^{12} and k^{13} . This 70 will cause the circuit $+A$ B C d^1 d^2 d^3 g^3 M k^{18} k^{15} k^{12} k^{11} k^{13} k^{16} N C —to be closed 75 so that the magnet coil g^3 will be under the full voltage and open the auxiliary cutout G . However, a certain although short time, 80 known as switch-lag, will pass between the moment the said circuit is closed and the moment at which the break of the motor circuit is terminated, this lag being due to the mechanical inertia of the cut-out G , the 85 magnetic inertia of its magnet coil g^3 and the inductive resistances existing in the main circuit. According to experience, this switch-lag is mostly considerably longer than the time that is necessary, in switching by jerks, for moving the controller into the position corresponding to the next lower switch step. In order to prevent injurious 90 arc-formations at the main current contact members of the controller, provision has 95 therefore to be made for allowing a returning of the switch drum K from a higher to a lower switch step only after the motor current has disappeared or at least not sooner than the motor current has dropped 100 below the predetermined maximum value. This is automatically obtained by the intermediary of the electromagnetic locking device F f^1 , P P^2 , k^{22} . For as long as the 105 current flowing through the coil f^1 still exceeds the admissible maximum value, the magnet armature p^4 as well as the magnet armature q^4 are attracted and the pawl P^2 is held in engagement with the teeth k^{22} so that a rotation of the switch drum opposite 110 to the direction of the arrow α , that is, towards its zero-position, is rendered impossible. As will be evident from what has been said, a further movement of the switch drum K in the said direction can only take 115 place when the strength of current in the motor circuit has dropped below the said maximum value. As soon as this takes place, the power of the spring R will overcome that of the magnet F f^1 so that the 120 pawl P^2 is again placed out of engagement with the teeth k^{22} . In the said positions of the switch drum the likewise attracted magnet armature q^4 does not execute any locking 125 action, since the teeth k^{23} are not in reach of the pawl Q^2 .

The described device will operate entirely similarly when using the controller K K^1 for braking electrically, in which case the motor H H^1 operates as generator on the 130

starting resistance E through the auxiliary cut-out G and the magnet coil f^1 . If the controller should be returned from a position which corresponds to a strong braking, 5 to a lower braking step, the regulating lever K^1 which had been moved opposite to the direction of the arrow α for instituting the braking action, must be turned back in the direction of the arrow α . This movement 10 is, however, automatically rendered impossible by the locking device $F f^1, Q Q^2, k^{23}$ until the motor current has dropped below the predetermined maximum value. As long as the motor current still exceeds this 15 maximum value, the force of the magnet $F f^1$ overcomes that of the spring R and the armature q^4 remains attracted and the pawl Q^2 engaged with the teeth k^{23} . As long as the locking device $F f^1, Q^2, k^{23}$ is operative, the narrow pitch chosen for the teeth k^{23} will not allow the regulating lever K^1 to approach to the stop k^5 to such an extent that the rod k^{11} will abut against the contact members k^{13}, k^{14} and thus close the circuit 20 containing the contact members k^{12} to k^{14} . The regulating lever K^1 may, at the most, move with relation to the pawl Q^2 by a fraction of the pitch of the teeth k^{23} , if the pawl Q^2 is not just opposite to a tooth space. 25 The controller is therefore forced to remain in the switch step once set until the braking current has dropped below the predetermined maximum value. As soon as this occurs, the magnet $F f^1$ will release the armature q^4 and the pawl Q^2 will again come out of engagement with the teeth k^{23} under the influence of the spring R.

The main advantage of the described device resides in the fact that an abnormally 40 rapid returning of the controller is rendered impossible in driving as well as in braking, thereby securely avoiding onerous and injurious arc-formations at the main current contact members of the switch drum and at 45 the auxiliary cut-out G. A special advantage of the described locking device resides in the fact that the driver, when properly handling the controller, does not at all become aware of the locking device, which will 50 only enter into action when the switching operations are executed at an improperly high speed.

Without changing the spirit of the invention, one of the locking devices, such as $P^2 k^{22}$, may be omitted and one may restrict oneself to protect the controller $K K^1$ and the auxiliary cut-out against arc-formation only in braking electrically. In this case, 55 for example, if it is intended to lock the controller electromagnetically in the braking positions but not in the driving positions, the auxiliary cut-out G g^2 might also be dispensed with and the regulating lever K^1 rigidly coupled with the switch drum K. 60 However, the use of a double locking device 65

and of the auxiliary cut-out afford the guarantee that even the slightest injurious arc-formation is kept away from the controller.

If the controller should not be used at all or only exceptionally for electrical braking, 70 the electric connections can be changed, without departing from the nature of the invention, in such a manner that the auxiliary cut-out G is only made use of in driving and not in braking. In this case, one of the three contact bars of the auxiliary switch device at the switch drum and the corresponding wiper can be dispensed with. This embodiment affords the further advantage that the overload circuit breaker D can 75 then be used as auxiliary cut-out instead of the auxiliary cut-out G, this being rendered possible by connecting the holding coil d^4 of the breaker D with the auxiliary cut-out in such a manner that it may serve at the same 80 time as releasing coil.

Finally, it must be remarked that the magnet coil f^1 can also become currentless by releasing the main current coil d^1 of the overload circuit-breaker D. In such case, 85 however, the driver can restore the main circuit only when he has returned the controller into its zero-position and thus broken the main circuit also at the switch drum, thereby making the holding coil d^4 currentless. The motor and the controller are thus 90 protected from injuries by abnormal strengths of current.

Claims:

1. The combination with a switch drum 100 for starting and controlling motors, comprising a driving member for said drum, of a single acting magnetic locking device for preventing said driving member from return movement, said device being kept in its locking position by the armature current of the motor to be controlled when exceeding a predetermined value, said locking device comprising a magnet to be energized by said armature current and two cooperative elements, one of these elements being formed by said driving member and the other element being placed under the influence of 105 said magnet.

2. The combination with a switch drum 110 for starting and controlling motors comprising a regulating lever mounted to rotate freely with relation to the switch drum for a small angle and an auxiliary switch device adapted to actuate a cut-out arranged in the motor circuit at a point outside the controller upon returning the regulating lever from any of its driving or braking positions, of a single acting electromagnetic locking 115 device including a magnet adapted to be energized by the armature current of the motor to be controlled and two cooperative elements, one of these elements being formed by the regulating lever of the switch drum 120 and the other element being placed under 125

the influence of the said magnet, and another single acting electromagnetic locking device arranged oppositely to the first mentioned locking device and, including also two co-operative elements, one of these elements being formed by the switch drum and the other element being likewise placed under the influence of the said magnet.

3. The combination with a switch drum for starting and controlling motors comprising a regulating lever, of two single acting electromagnetic locking devices, an

auxiliary cut-out arranged in the motor circuit at a point outside the controller, and an auxiliary switch device for cooperation 15 with the switch drum and for causing the auxiliary cut-out to enter into action only upon moving the said regulating lever back from any of its driving positions.

The foregoing specification signed at 20
Essen, Germany, this 4th day of September,
1922.

LUDWIG SCHÖN.
